His Attorney.

UNITED STATES PATENT OFFICE

NEVILLE RYLAND DAVIS, OF SALE, ENGLAND, ASSIGNOR TO GENERAL ELECTRIC COMPANY, A CORPORATION OF NEW YORK

FURNACE TAPPING DEVICE

Application filed October 23, 1930, Serial No. 490,762, and in Great Britain November 4, 1929.

My invention relates to furnace tapping devices, more particularly to furnace tapping devices which are intended to be used at or near the bottom of a furnace, and has for its object the provision of an improved device of this character.

According to one form of my invention, the melting furnace has an orifice at the place where it is desired the furnace should be tapped and a two-part plug is provided, one part forming the end thereof being adapted to fit substantially the tapping orifice, and the other part being arranged so that a circulation of cooling fluid can be maintained there-through or therearound.

The two parts of the plug are either maintained in close contact or are detachably connected by a joint, a soldered joint for example, so that a sufficiently good heat conducting path is formed to prevent the solid part of the plug from melting so long as the cooling circulation is maintained about the other part. When the plug is in position in the tapping orifice the solid portion being cooled will prevent leakage of metal around the plug by solidifying the molten metal immediately around the end within the wall of the furnace.

When it is desired to pour the furnace the circulation of cooling fluid through or around the plug is stopped and the fluid cooled part of the plug removed from the other part. Where the two parts are soldered together the joint will melt when the cooling circulation has ceased. After a certain interval of time depending upon the size of the solid portion and the material of which it is made this portion will be melted by the molten metal above and the furnace is poured. After the furnace has been poured the fluid cooled portion of the plug may be provided with a fresh solid part and inserted in the tapping orifice from the outside of the furnace, which is then ready for a fresh charge.

The fluid cooled part of the plug forms a means by which the cooled portion may be inserted in the tapping orifice and in some cases may not be attached to the solid part of the plug.

For a more complete understanding of my

invention reference should be had to the accompanying drawing in which the single figure illustrates in vertical section the bottom portion of a metal melting furnace provided with a tapping device embodying my invention.

In the drawing, it will be understood that the furnace walls comprise an inner lining or crucible 10 which is made of any suitable refractory material, and an outer lining 11 which may be made of refractory brick or sand or any suitable materials such as are used in the construction of melting furnaces. An outer casing 12 is provided for the furnace linings which casing in some instances may be made of metal plate or straps. A comparatively large aperture, indicated at 13, is provided in the furnace lining and brick bottom, and within the aperture is what may be termed a nozzle 14 which is conveniently formed of fire clay, or some suitable similar material, and supported by the casing 12 as shown. The nozzle is formed with a tapered opening therethrough to accommodate the tapping plug and also a filling 15 which may be of gannister or silica, or other material suitable for the purpose.

The tapping device comprises a plug which is formed in two parts, a solid part 16, which closes the inner portion of the tapping orifice 17 and which preferably is formed of a material similar to the metal to be melted, and a hollow tubular-like part 18 which may be of copper. The hollow member 18 in the example shown is united to the solid part 16 by a soldered joint 19 and is provided with an internal tube 20 so that a circulation of cooling fluid, water for example, may be maintained in a well known manner which need not be further described. It will be observed, however, that the tubular member 18 is provided with a tubular fluid outlet 21 which may be and as shown is formed integrally with the tube 18. The arrows in the drawing indicate the direction of motion of the cooling fluid.

The inner end of the tapping orifice 17 may be flared as shown so as to afford an easy path for the melted charge to flow out when the furnace is being poured. The entire furnace

is raised a convenient distance from the ground on feet (not shown), or is supported in a framework or cradle (not shown), so that sufficient room is afforded below the bottom to admit of manipulation of the plug and also to permit a mould or conduit to be placed in position into which the melted charge can flow when the furnace is tapped.

In preparing the furnace for operation, 10 the two-part plug is inserted in the tapered opening in the nozzle, and gannister or silica or other material indicated at 15 is rammed therearound so as to retain it in position. In general the plug will only be required to 15 be held in position during the charging into the furnace of the material to be melted, and owing to the comparatively small area of the plug the weight tending to force it out of the orifice before the bottom part of the 20 charge is melted will be small. The furnace having been charged with material, cooling water is circulated through the lower tubular portion 18 of the plug from any suitable source, and owing to the good thermal conductivity between this lower part of the plug and its solid part 16, the solid portion will be maintained cool even after the furnace charge has melted. Usually it will be found 25 that as the charge melts and runs down into the portion of the orifice immediately surrounding the solid part 16 of the plug it will solidify by reason of the cooling effect of said solid portion and will form a button which will effectually seal the orifice 17.

30 When it is desired to tap the furnace, the water circulation is stopped and the heat from the molten charge is communicated through the solid portion 16 of the plug to the joint 19 and melts the solder, whereupon 35 the hollow part 18 of the plug can be withdrawn and after an interval of time the solid part 16 and the button of solidified metal around it will be melted by the heat of the charge and the furnace will empty through 40 the orifice 17. The solid portion of the plug will be absorbed in and come away with the charge.

45 During the pouring it generally happens that a part of the lining 15 of the aperture in the nozzle is carried away by the stream of molten metal. The nozzle, however, will generally last for several melts, but may, of course, be replaced at any time and particularly when relining the furnace. The lower or hollow part 18 of the plug may be used again by providing it with a fresh solid portion 16 and the plug reinserted when preparing the furnace for a fresh charge.

50 In some cases soldering at the joint 19 may be dispensed with if a sufficiently good thermally conductive contact is maintained between the two parts of the plug to enable a proper cooling of the solid part 16 to take place.

55 Instead of circulating a cooling liquid

through the lower part of the plug it may in some cases be sufficient to circulate air or a cooling gas through said part, the velocity of the current through the plug depending, of course, on the amount of cooling which is 60 required.

65 As it is desirable in all cases that when it is determined to tap the furnace a rapid change in the temperature of the plug shall 70 take place when the cooling is discontinued so that the cooled portion may be removed and the furnace teemed with as little loss of time as possible, the plug is preferably constructed to enable this to be effected.

75 In designing the plug, therefore, the following points should be borne in mind. The soldered joint when employed must not melt while being cooled, consequently the cooling must be capable of removing heat at a considerable rate, that is, the cooling must be exceedingly effective and the cooling fluid must be able to dissipate a considerable amount of energy. On the other hand, the inner portion 80 of the plug must not be too long, otherwise, when the cooling is stopped the time taken to melt the plug before teeming can take 85 place would be excessive and occasion a great waste of time. It is clear, therefore, that the rate of removal of energy by the cooling system is very important, and very effective 90 cooling must be employed especially in view of the comparatively small area of the plug available on which the cooling fluid can impinge.

95 The invention is very suitable for use with 100 electric furnaces particularly of the induction type, and in such cases the plug may advantageously be connected to earth for the purpose of earthing the charge as indicated by the numeral 22 in the drawing.

105 While I have shown a particular embodiment of my invention, it will be understood, of course, that I do not wish to be limited thereto since many modifications may be made, and I, therefore, contemplate by the 110 appended claims to cover any such modifications as fall within the true spirit and scope of my invention.

115 What I claim as new and desire to secure by Letters Patent of the United States is:

120 1. A tapping device for a melting furnace provided with an orifice therein comprising a metallic plug member adapted to close said orifice and means for cooling said member so as to maintain the furnace charge adjacent 125 said plug and in contact therewith in a solidified condition as long as said plug is cooled.

130 2. The combination with a furnace provided with a tapping orifice, of a plug for said orifice comprising a portion arranged to close said orifice and projected into said furnace and means for bringing a cooling medium into contact with said orifice closing portion as that the metal surrounding said projecting portion is maintained in a solidi-

fried condition as long as said portion is cooled but is melted when said cooling medium is removed.

3. A melting furnace comprising walls having a tapping orifice therein, a member substantially closing said orifice, a second member, binder metal having a lower melting point than said first member between said first and said second members, and means for cooling said second member.

4. The combination with a melting furnace provided with walls having a tapping orifice therein, of a plug for said orifice comprising a substantially solid metallic portion positioned in said orifice so as to substantially close it and a second metallic portion in heat conducting relation with said first portion, said second portion having a conduit therein through which a cooling medium can be circulated, whereby that portion of the furnace charge in contact with said first portion is maintained in a solid state.

5. A furnace comprising walls having a tapping orifice therein and a tapping device for closing said orifice comprising a plug having a substantially solid portion adapted to be fitted into said orifice so as to substantially close said orifice, a tubular portion detachably connected to said solid portion in good thermal relation therewith and means for circulating a cooling fluid through said tubular portion.

6. The combination with a metal melting furnace having walls provided with a tapping orifice therein, of a tapping device for closing said orifice comprising a plug-like member, said plug-like member being formed from a material similar to the metal to be melted and means for circulating a cooling medium to cool said plug-like member so that that portion of the furnace charge in contact with said member is maintained in a solidified condition as long as said member is cooled but is melted and with it said plug when the circulation of said cooling medium is stopped.

7. A melting furnace comprising walls having a tapping orifice therein, and a plug for closing said orifice, said plug having a portion adapted to be fitted into said orifice so as to substantially close said orifice, a tubular portion, binder metal of a lower melting point than said plug between said plug and said tubular portion and means for circulating a cooling fluid through said tubular portion.

8. A metal melting furnace comprising walls having an aperture therein, a nozzle in said aperture, a heat refractory material in said nozzle forming an orifice therethrough and a plug for closing said orifice comprising a substantially solid metallic portion arranged to be fitted in the inner end of said orifice so as to substantially close said inner end, a tubular member secured to said solid

portion and projecting outwardly from said orifice, a second tubular member within said first tubular member for conveying a fluid medium therethrough, and means providing for the passage of said fluid medium from said first tubular member.

9. A metal melting furnace comprising walls provided with a nozzle-like aperture therein and a tapping device for closing said aperture comprising a plug-like member arranged in said aperture so as to substantially close said aperture and having a substantial portion projecting into said furnace, and means for cooling said plug-like member so that the metal surrounding said projecting portion is maintained in a solidified condition while said member is cooled.

10. The combination with a metal melting furnace having walls provided with a tapping orifice therein of a tapping device for said orifice comprising a plug adapted to be inserted in said orifice so as to substantially close said orifice and so that a portion of said plug is in electrical contact with the furnace charge, means for cooling said plug and means including said plug providing a grounding circuit for said furnace charge.

11. The combination with a metal melting furnace provided with walls having a tapping orifice therein, said orifice being provided with a portion flared toward the interior of said furnace, a cylindrical plug member arranged to close said orifice and having a portion embraced by said flared portion and means for cooling said plug so that the metal between said plug and the walls of said flared portion is maintained in a solidified condition as long as said plug is cooled.

In witness whereof, I have hereunto set my hand this thirteenth day of October, 1930.

NEVILLE RYLAND DAVIS.
